US0D1051291S

(12) **United States Design Patent** (10) **Patent No.:** **US D1,051,291 S**
(45) **Date of Patent:** **** Nov. 12, 2024**

(54) **FILTER CORE FOR POT**

(71) Applicant: **Qingdao Ecopure Filter Co., Ltd.**,
Qingdao (CN)

(72) Inventor: **Zhibin Zou**, Qingdao (CN)

(73) Assignee: **Qingdao Ecopure Filter Co., Ltd.**,
Qingdao (CN)

(**) Term: **15 Years**

(21) Appl. No.: **29/907,578**

(22) Filed: **Jan. 8, 2024**

Related U.S. Application Data

(63) Continuation of application No. 29/813,949, filed on
Nov. 2, 2021, now Pat. No. Des. 1,016,971.

(57) **CLAIM**

The ornamental design for a filter core for pot, as shown and described.

DESCRIPTION

FIG. 1 is a front elevation view of an embodiment of a filter core for pot showing my new design;

FIG. 2 is a rear elevation view of the filter core for pot;

FIG. 3 is a left side elevation view of the filter core for pot;

FIG. 4 is a right side elevation view of the filter core for pot;

FIG. 5 is a top plan view of the filter core for pot;

FIG. 6 is a bottom plan view of the filter core for pot;

FIG. 7 is a top, front, left side perspective view of the filter core for pot; and,

FIG. 8 is a bottom, front, left side perspective view of the filter core for pot.

The broken lines showing portions of the filter core for pot form no part of the claimed design.

1 Claim, 8 Drawing Sheets
